UNITED STATES PATENT OFFICE.

FERDINAND EGGERS, OF DENVER, COLORADO.

QUICK-ADJUSTMENT WRENCH.

1,117,173.

Specification of Letters Patent. Patented Nov. 17, 1914.

Application filed June 17, 1913. Serial No. 774,122.

To all whom it may concern:

Be it known that I, FERDINAND EGGERS, a citizen of the United States of America, residing in the city and county of Denver 5 and State of Colorado, have invented a new and useful Quick-Adjustment Wrench, of which the following is a specification.

This invention relates to improvements in wrenches.

- 10 The object of the invention is to provide a wrench, the movable jaw of which may be instantaneously slid from one point of adjustment to another, and locked at the desired point against accidental movement.
- 15 Further, to provide a wrench to the movable jaw of which is pivotally attached an operating arm or lever having a wedge-shaped projection, the handle of said wrench being hollow and slotted on the side next the said 20 projection, said handle having spring-pressed spacing disks therein between any two of which the said wedge-shaped projection is passed, by pressing on the handle or lever, whereby the movable jaw is held 25 at the desired point of adjustment, means also being provided for moving the disks to effect an adjustment of less extent than the thickness of one of the disks. These 30 objects are accomplished by the mechanism illustrated in the accompanying drawings, in which:

Figure 1, is a perspective view of the improved wrench. Fig. 2, is a vertical, sectional view of the same. Fig. 3, is a transverse sectional view thereof, on the line 3—3 of Fig. 2. Fig. 4, is a side view of the head portion of a pipe wrench, showing the adaptation thereto of my improved spacing and locking mechanism, and Fig. 5, is a transverse sectional view thereof on the line 5—5 of Fig. 4.

Similar letters of reference refer to similar parts throughout the several views.

Referring to the drawings, the numeral 45 1, indicates the handle, and 2 the shank of a wrench of the style commonly designated as monkey wrenches. The shank is unthreaded, and upon the same is slidably mounted the adjustable jaw 3. The head 50 or stationary jaw 4, may be welded upon the outer end of the shank, after the adjustable jaw has been placed on the said shank; or the head 4 may be integral with the shank, and the slot in the adjustable or sliding jaw may be extended out through 55 its rear end, so as to permit of its being

placed upon the shank, after which a metal block may be welded or otherwise secured in the said slot, to form the rear end wall of the rectangular aperture in the said jaw, 60 as will be understood, this feature forming no part of the invention.

To the rear end of the sliding jaw, and preferably at the lower corner thereof, is pivotally secured the upper end of an arm 65 or lever 5, which is preferably of a length to extend to or nearly to the lower end of the handle, when the sliding jaw is at the limit of its upward movement. Intermediate of the ends of this lever, and from the side 70 thereof next the handle of the wrench, projects a wedge-shaped shoe 6, the purpose of which will be hereinafter explained.

The handle of the wrench is formed with a cylindrical bore 7, which extends through the lower end thereof, and the lower portion 75 of this bore is threaded for a suitable distance from the end of the handle. Into this threaded lower end of the handle, is screwed a plug 8, which is preferably formed with 80 a central threaded portion 9, the parts of the plug on opposite sides of the threaded portion being of less diameter than the threaded portion 9. This arrangement permits a stop pin 10 to be passed through the 85 handle below the said threaded portion 9, which prevents the plug from being detached from the handle. It also permits the upper end of the plug to extend above the threaded portion of the bore, to form 90 a base or abutment for a plurality of disks or washers 11, which are placed one upon another within the bore of the handle. These washers are sufficient in number to extend to within a short distance of the 95 upper end of the said bore, and between the topmost washer and the upper end of the bore is interposed an expansion coil spring 12, which holds the washers under sufficient pressure for the purpose required. These 100 washers are provided with the usual central apertures 13, the marginal edges of which are preferably flared or beveled, as shown.

The side of the handle next the lever 5, is provided with a longitudinal slot 14, a portion 105 of which opens into the bore 7. The part of this slot which opens into the bore, extends from a point on a level with the upper end of the plug 8, to within a short distance of the upper end of the bore 7, and 110 is of a width corresponding to that of the shoe 6 on the lever 5. Along the inner edge

2
of the lever 5, is formed a rabbeted projection 15, of the same width as the shoe 6, and from which the shoe projects. This rabbeted projection extends into the outer portion of the slot 14, when the lever is in its closed position, as shown in Fig. 2. When the lever 5 is closed against the handle, the wedge-shaped shoe passes in between any two disks or washers in line with the point of

10 said wedge, and the washers above the shoe are forced up against the pressure of the spring 12, while those below the wedge form a solid base or abutment for the same, which prevents downward movement of the sliding jaw. A lug 16 is formed on the upper face of the wedge, which is sprung into the aperture 13, in the contacting washer, when the handle is closed, and thereby locks the same against accidental opening. The flaring

20 margin of the apertures 13 permits the lug 16 to become readily disengaged therefrom.

In operation, the wrench handle is grasped by one hand and the lever 5 is opened and held by the other hand. The wrench is then 25 placed upon the nut or other object to be turned, and the sliding jaw 3 is moved up against the said nut by means of the lever 5, until the nut is clamped between the two jaws 3 and 4. The lever is then closed; the 30 wedge 6 passing between the two washers in line with its point, until its lug 16 springs into the aperture of the upper contacting washer when the lever is locked. Should the jaws grip loosely upon the nut and a close 35 or tight grip is desired, it is only necessary to screw in, slightly, the plug 8, in the lower end of the wrench handle, whereby the washers, with the lever and jaw 3, are raised, so as to tightly clamp the nut between the sliding and fixed jaws, as will be understood by 40 reference to Fig. 2.

The plug 8 is provided with a thumb piece 17, by which the plug can be conveniently turned in either direction.

45 In Figs. 4 and 5, I have shown the adaptation of my improvement to an ordinary pipe wrench. In this arrangement, the shank 18 of the wrench is provided with a pivoted block 19, which carries the movable jaw 20, the shank 21 of which is slidably mounted 50 in the said block 19. The shank 18 is hollow and is partially filled with washers 22, which are held under pressure by a spring 23, the washers resting upon a threaded plug 24, the said plug, washers and spring being 55 similar in all respects to those shown in Fig. 2. To the front end of the block 19 is suitably hinged an arm 25, provided with a projecting wedge 26, similar to the wedge 6 in 60 Fig. 2, the wedge 26 having a slightly pro-

jecting lug 27 on its upper side. When the arm 25 is in a closed position, it lies along one side of block 19, as shown in Fig. 5, and its wedge 26 passes through a slot 28 in the side of the shank 18 and between the 65 washers 22, the same as in Fig. 2. The block 19 may be provided with a groove or recess to receive the arm 25, so that the said arm may lie flush with the face of the block when closed, as shown.

70 With a wrench constructed as herein described, not only can adjustments of the sliding jaw and the locking of the same be quickly and easily accomplished, but the arrangement is such that the lever cannot become accidentally unlocked under ordinary 75 conditions; and hence the movable jaw is held at the exact point of adjustment for any required length of time.

Having described my invention, what I 80 claim as new and desire to secure by Letters Patent, is:

1. The combination with a wrench comprising a hollow handle slotted on one side, a shank, a fixed jaw at the end of the shank 85 and a jaw slidable on the shank, of a plug threaded and adjustable in the lower end of the handle, a column of centrally apertured washers in said handle which rest upon said plug, an expansion spring for exerting 90 downward pressure on said washers, a lever pivoted at one end to said slidable jaw, having an inwardly projecting wedge and a catch lug on said wedge, whereby when the lever is closed against the handle the wedge 95 passes through the slot therein and between the disks, the catch lug springing into the aperture of the contacting washer and locking said handle.

2. The combination with a wrench having 100 a slidable jaw and a hollow handle, of a column of knife-edged washers in said handle having central apertures with flaring marginal edges, an expansion spring which exerts a downward pressure on said washers, a 105 lever pivoted to said jaw, a wedge projecting from said lever, and a catch on the upper side of said wedge, said wedge being adapted to pass between the washers at any point, when the arm is closed, the under washers forming an abutment and the lever being locked by the springing of the catch into the aperture of the upper contacting washer.

110 In testimony whereof I affix my signature in presence of two witnesses.

FERDINAND EGGER.
